UNITED STATES PATENT OFFICE.

CHARLES H. HUBBELL, OF DERBY, CONNECTICUT, ASSIGNOR TO THE
STERLING CO., OF DERBY, CONNECTICUT, A CORPORATION.

PEDAL ATTACHMENT FOR PNEUMATIC INSTRUMENTS.

No. 833,215.

Specification of Letters Patent.

Patented Oct. 16, 1906.

Application filed February 12, 1906. Serial No. 300,646.

To all whom it may concern:

Be it known that I, CHARLES H. HUBBELL, a citizen of the United States, residing at Derby, in the county of New Haven and State of Connecticut, have invented a new and useful Improvement in Pedal Attachments for Pneumatic Instruments; and I do hereby declare the following, when taken in connection with the accompanying drawings and the numerals of reference marked thereon, to be a full, clear, and exact description of the same, and which said drawings constitute part of this specification, and represent, in—

Figure 1, a side view of one of the treads of my improved pedal attachments, showing its location with relation to the pneumatic instrumentalities and to the case of the instrument in which it is used; Fig. 2, a top or plan view of the pedals in an open position, one of the treads broken away to show the manner of connecting the two parts thereof; Fig. 3, a broken top or plan view of the inner end of one of the toe portions, showing the connections therewith to one of the feeders; Fig. 4, a side view of the parts shown in Fig. 1 in their closed or retired position.

This invention relates to an improvement in pedal attachments for pneumatic instruments, and, while adapted for pneumatic instruments of various characters, is especially applicable for pneumatically-operated pianos and in which the pneumatic instrumentalities are arranged within the piano-case. In such instruments it is desirable, not to say necessary, that the pedals for operating the pneumatic instrumentalities shall be folded into the case for convenience in shipping, and especially to give access to the regular pedals of a piano when the pneumatic instrumentalities are not in operation. In many instruments the exhaust-chamber of the pneumatic action is arranged in the case below the keyboard, so that comparatively little space can be utilized for the pedals.

The object of this invention is to arrange the pedals so that they may be conveniently and easily retired and brought into operative position and when retired occupy but very little space in the case; and the invention consists in the construction, as hereinafter described, and particularly recited in the claims.

The treads are divided transversely into two sections, which are called the "heel-sections" 2 and the "toe-sections" 3, the two be-

ing hinged together at the center, so as to fold upward, the hinge-pin 4 being below the plane of the treads, and on this pin is a spiral spring 5 so connected at their ends as to normally hold the treads in an open position. The heel portions 2 are pivoted to the rod 6, which connects the outer ends of arms 7, which at their outer ends are adapted to rest upon the floor and at their inner ends are connected to links 8, which in turn are pivoted to brackets 9, secured to the front face of an exhaust-chamber 10, the inner ends of the links having offset arms 11, which are connected together by a brace-rod 12. The arm 7 is formed at its inner end with a stop-finger 13, which bears against the inner edge of the link 8. The toe portions 3 are connected by curved levers 14 with brackets 15, secured to the movable portion 16 of the feeders, it being understood that the feeders are arranged on opposite sides of the central opening in the front of the case, through which the pedals extend, the exhaust-chamber 10 being also cut away to give sufficient clearance. The bracket is provided with a lug 17 to limit the movement of the lever 14 when folded and with a stud 18, against which the finger 19 on the lever 14 will engage when open. As indicated above, the front 20 of the case is cut away above the piano-pedals 21, which opening may be closed in any desired manner. As shown in Fig. 1 of the drawings, the treads are in an operative position and pressure upon the toe of the treads will force the movable member of the feeders rearward, or, in other words, operate in the usual manner of pedals for pneumatic instruments.

To retire the pedals, the treads are broken upward and the bar 6 raised, causing the arms 7 to turn upon their pivots with the links 8 and the links upon their pivots with the brackets 9, while the toe portion turns with respect to the bracket 15, but without changing the position of the movable part of the feeders. The treads of the pedals thus fold inward between the feeders and below the central portion of the exhaust-chamber. The upper end of the lug 17 forms a stop to limit the inward movement of the treads, as in the retired position, as shown in Fig. 3 of the drawings. The edge of the levers 14 will bear upon the upper ends of these lugs 17. When thus retired, the opening in the case may be closed and the pedals 21 of the piano operate

in the usual way. The pedals are withdrawn to the operative position by simply grasping the bar 6 and drawing it outward, which brings the treads to an operative position and without disturbing the movable member of the feeders.

I claim—

1. In a pneumatic instrument a case, in combination with feeders arranged on opposite sides of the center of the case, pedals arranged to move in a path located laterally to the path of the movable portions of said feeders, the treads of the pedals divided transversely, arms with which the heel portions of the treads are pivotally connected, said arms extending inward, links with which said arms are engaged, said links connected with a fixed point inside the case, levers connected with the toe portions, and brackets secured to the movable member of the feeders, said levers and brackets connected, substantially as described.
2. In a pneumatic instrument a case, in combination with an exhaust-chamber and feeders, the lower central portion of the exhaust-chamber being cut away and the feeders being arranged on opposite sides of said cut-away portion, pedal instrumentalities comprising treads transversely divided, arms pivotally connected with the heel portions of the treads, links with which the inner ends of said arms are pivoted, brackets secured to the front wall of said exhaust-chamber, said links connected with said brackets, said links formed with arms, a rod connecting said arms, levers with which the toe portions of the treads are connected, brackets secured to the movable members of the feeders, said levers and brackets connected, substantially as described.
3. In a pneumatic instrument, a case, in combination with an exhaust-chamber and feeders, the lower central portion of the exhaust-chamber being cut away, and the feed-

ers being arranged on opposite sides of said cut-away portion, pedal instrumentalities comprising treads transversely divided, a spring-hinge connecting the two portions of each tread, arms with which the heel portions of the treads are pivotally connected, links to which the inner ends of the said arms are pivoted, brackets secured to the front wall of said exhaust-chamber, said links being connected with said brackets, and having arms, a rod connecting said arms, levers with which the toe portions of the treads are connected, and brackets secured to the movable portions of the feeders, said levers and brackets being connected, substantially as described.

4. In a pneumatic instrument a case, in combination with an exhaust-chamber, and feeders, the lower central portion of the exhaust-chamber being cut away, and the feeders being arranged on opposite sides of said cut-away portion, pedal instrumentalities comprising treads transversely divided, arms connected with the heel portions of the treads, links connected with the inner ends of said arms, brackets secured to the front wall of said exhaust-chamber, said links and brackets being connected together, said links having arms, a rod connecting said arms, links connected with the toe portions of the treads, brackets secured to the movable members of the feeders, said treads and brackets being connected, and said brackets being formed with a lug to limit the inward movement of the links connected with the toe portions, substantially as described.

In testimony whereof I have signed this specification in the presence of two subscribing witnesses.

CHAS. H. HUBBELL.
